UNITED STATES PATENT OFFICE.

WILLIAM B. PEIRCE, OF NORTH TONAWANDA, NEW YORK, ASSIGNOR TO BUFFALO BOLT COMPANY, OF NORTH TONAWANDA, NEW YORK, A CORPORATION OF NEW YORK.

METHOD OF HEATING COILED MATERIALS.

1,243,444.

Specification of Letters Patent. Patented Oct. 16, 1917.

Original application filed November 10, 1911, Serial No. 659,487. Divided and this application filed January 26, 1916. Serial No. 74,330.

To all whom it may concern:

Be it known that I, WILLIAM B. PEIRCE, a citizen of the United States, residing at 145 Bryant street, in North Tonawanda, in the county of Niagara and State of New York, have invented certain new and useful Improvements in Methods of Heating Coiled Materials, of which the following is a specification.

10 This method concerns progressively heating a continuous length of material while feeding it into, through and out of a furnace. It involves a method of handling the material, which though useful for other purposes, is particularly adapted for furnaces and operations where the metal is heated to a very high temperature, particularly where heated up to the softening point. Effective heating to such temperatures requires that 15 the metal passing through the furnace be kept freely exposed on all sides to a very high heat for a considerable time. To do this with the metal passing straight through the furnace would require either a very slow 20 feed or a very long furnace, whereas it is desirable to use a relatively small, compact furnace and to give the metal a desired high rate of feed into and out of the furnace combined with a relatively slow rate of pro- 25 gress through the furnace.

For some purposes, it has been proposed to accomplish this by giving the metal a straight feed into and out of the furnace, the intermediate portions being wound tightly 30 around a revolving drum within the furnace. Such method involves extensive contact of the metal with the drum and prevents its free exposure and uniform heating on all sides. On the other hand, winding 35 the metal in large, open, freely suspended coils in accordance with my present method has not heretofore been attempted because of the difficulties resulting from the initial stiffness of the metal and the effect of the 40 heat in softening it.

My method, while capable of useful employment for operations permitting tight winding of the material on the drum, is of much greater importance and usefulness for 45 operations requiring free suspension and exposure of the metal for effective, uniform, high temperature heating. It involves giving to the material fed into the furnace a predetermined initial shape and set in the

curvature of a coil or helix of desired diameter and length suitable to the stiffness of the material and the size of the furnace. This material is wound into the furnace so that it hangs loosely from a suitable support and, though the material is more or less flexible, the construction of the support is such as to permit the successive turn to assume and maintain a curvature and spacing roughly approximating the coil or helix shape originally given it.

By suitably predetermining the length of the interior support and the number of turns of the helix hanging thereon, the length of time required for travel of each turn through the furnace may be as long as necessary. Hence, it is possible to maintain the required rate of output of heated material while using a relatively small, compact furnace.

Because of the effect of the heat upon the coiled material in softening it, it is necessary to carefully control the rates of movement of the metal at the supply end and the exit end, so that it will be unwound from the exit end of the helix by the time it has become softened to the proper degree and before it becomes too soft to maintain proper separation of the turns of the helix.

The material is uniformly heated because the amount of it which actually touches the support is small and the point of contact is more or less shifting.

The material to be heated may be supplied in ready formed coils containing any desired length of the material preferably the ordinary commercial coils obtainable from the rod mills. Such material already has an initial shape or set of approximately the curvature of the coil in which it is marketed and such curvature or set is utilized in the formation of the desired helix within the furnace, without unwinding the coil, the successive turns being progressively opened out, and the metal given a slight set or bend axially so that it will tend to maintain the helical or corkscrew shape and spacing during its progress along the support within the furnace.

By the expression "without unwinding the coil" I mean that the circularly curved set or shape is not taken out of the material while advancing it from the exterior to the interior of the furnace.

The transfer of the material from the exterior coil to the interior helix may be effected with or without change in the diameter of the turns, through an oblique opening 5 into the furnace, and this opening need not be of much greater diameter than the thickness of the material.

This new manipulation or method of handling coiled materials consists essentially in the separation of the coil into its 10 several turns. This is done by extending the coil in the direction of its axis.

As will be readily understood, if the first 15 turn at the end of the coil is drawn in the direction of the axis of the coil, that turn so drawn, will be separated from the remainder of the coil and is able to be heated separately at its extended part. Then by 20 passing this movement of axial extension along the material of the coil to its successive portions, these successive portions will be successively extended axially and may be successively heated.

This is the principal operation upon which 25 this invention depends, and this operation may be performed by the naked hand of an operator, and the means of heating may be applied in the same manner, no mechanism being required.

30 My above described method for progressively heating coiled material may be used for any desired purpose but it is particularly applicable to the heating of iron until it is soft enough for forging operations. In 35 such case, it saves the necessity of straightening and cutting the coiled material into lengths, heating it in long furnaces and transferring it by hand to the automatic forging machine or other apparatus in which 40 it is to be used.

For the commercial use of this process and for its more rapid operation, and for the employment of more force which may be necessary in its application to heavy materials, I prefer to use some form of mechanical device to manipulate the coil and some form of furnace to furnish and apply the heat to the coiled material, and I have illustrated and present as a portion of this 50 specification, drawings and description of one form of furnace which will be found adequate to perform the operation above described.

In the employment of a furnace for this 55 purpose, certain details of my method have been developed and are described herein for the movement of such coiled material from the exterior to the interior of such furnace, which details of practice are the subjects 60 of some of the claims presented herewith.

The specific means for transferring the exterior coiled material into the furnace and for giving the successive turns the helical bend or offset, is shown herein as consisting 65 of feed mechanism operating to drive the

material endwise through a helical or corkscrew passage in the walls of the furnace. The longitudinal support within the furnace from which hang the helical coils and along which they move while being heated, is 70 shown as a rotating cylinder. The fully heated material is shown as being unwound and fed out, in a radial plane from the remote end of the helix. Other specifically different arrangements for accomplishing 75 the formation, support, axial travel and unwinding of the helix are shown in my co-pending application Serial No. 846,744, filed June 23rd, 1914.

My present apparatus and its method of 80 operation will be more fully understood from the following detailed description in connection with the accompanying drawings in which—

Figure 1 is a side elevation of a furnace 85 with my invention applied thereto, and

Fig. 2 is a plan view partly in section on the line 2—2 of Fig. 1.

In the drawings 6, 6, 6, 6, represent the 90 walls of a furnace made of fire resisting material and secured by an exterior frame, 7, 7, 7, 7.

The heating chamber within the furnace, is indicated at 30. A source of heat is supplied for said furnace chamber as indicated at 9.

It has a coil supporting member, 1, which is a cylinder mounted upon a shaft, 29, by which it is turned.

The coil to be heated is hung upon this 100 supporting member, 1, which is placed near the outside of the furnace and is supported upon the roller bearings, 32 32.

This shaft, 29, is turned by a sprocket, 11, driven by a chain, 25, from a driving 105 sprocket, 33, to which power is applied from a prime mover through the shaft, 34. 35 is a clutch. A feed controlling device is provided consisting of the feed rollers 15 and 16 which are mounted to revolve upon their 110 studs 17 and 18 respectively, being actuated by sprockets, 12 and 13 through the driving chain 25.

One of these feed rolls, as 15, is mounted upon a lever, 19, which is rotatable upon its 115 supporting stud, 20, and whose free end is capable of adjustment by a set screw, 21, so as to press more or less closely against its companion roller 16 to adapt it to feed various sizes of coiled material.

The rolls 15—16 feed the coiled material through the adjacent furnace wall and into the heating chamber 30 of the furnace.

A passage through said adjacent furnace wall, is supplied for this purpose, and this 125 passage is curved as is indicated at 36, 37, so that the coiled material may pass through it while still retaining its coiled form.

For ease of construction, I prefer to place in the furnace wall, an iron pipe as is illus- 130

trated at 36, 37, which pipe is bent to approximately the same curvature as the coiled material, and this pipe is so placed in the wall as to afford a lead to the coiled material in a direction toward the furnace chamber, 30.

The amount of lead in the inlet passage depends upon the thickness of the furnace wall, and upon the gage and stiffness of the 10 coiled material, since thin materials should be given a greater lead than thick ones in order to separate the turns more widely and so decrease the number of them, and hence the length of time they remain in the furnace.

After passing through the inlet opening 36, 37, the coiled material passes over a supporting member, 3, which is mounted within said furnace chamber upon the shaft, 29, 20 and which is made of a heat resisting material, and is also preferably supplied with a pair of collars as is indicated at 4 and 4', placed adjacent to the interior faces of the furnace walls, to prevent the coiled material 25 from falling into the spaces between said furnace walls and the ends of said supporting member 3.

Suitable driving means are supplied for 30 rotating this interior coil supporting member, and the drawings illustrate one form of such driving mechanism as consisting of the sprocket, 11, and drive chain, 25.

The material to be heated passes around 35 and hangs from this interior supporting member 3 in large depending coils freely exposed to the heat on all sides except at the top point where they rest upon the cylinder, the number of turns of the coil being such as will enable it to remain in the heating 40 chamber of the furnace long enough to be brought up to the desired temperature, after which it passes out from the furnace chamber, 30, through an orifice, 5, in the end wall of the furnace, in the direction of the 45 rotation of the sustaining member, 3.

Upon its emergence from the chamber, 30, the heated material is ready for any subsequent operation to which its heated condition adapts it.

50 I have preferred to make the supporting members 1 and 3, of equal diameter, and to rotate them at the same speed, and for simplicity, I have shown them as mounted upon the same shaft, 29, and driven by a single 55 driving member, sp ocket, 11, actuated by the drive chain, 25.

It will be understood, though, that separate driving members may be used for the exterior and interior coil supports.

60 The apparatus herein disclosed as suitable for practice of my method is claimed in application Serial No. 659,467, of which this application is a division.

While I have herein disclosed a specific 65 apparatus suitable for the practice of my

method and while I have disclosed with considerable particularity certain detail steps which may be employed in the practice of the same, it will be obvious nevertheless that the invention is a broad one and that certain of said specific steps may be omitted, or modified without departure from the spirit of my invention. For instance, the method as broadly defined in certain of my claims hereinafter set forth 75 may be practiced by utilizing the apparatus disclosed in my application No. 846,744.

Having thus described my invention, what I claim as new and desire to secure by Letters Patent, is:—

1. The method consisting in extending successive portions of a coil of material to be heated in an axial direction, without unwinding it, and heating such extended portions successively.

2. The method consisting in extending successive portions of a coil of material to be heated in an axial direction, without unwinding it, while maintaining a coiled form, and heating such extended portions.

3. The method consisting in extending successive portions of a coil of material to be heated in an axial direction, without unwinding it, maintaining the coiled form, and heating such extended portions successively.

4. The method consisting in extending a coil of material to be heated in an axial direction, without unwinding it, and progressively heating such extended material.

5. The method consisting in extending a coil of material to be heated in an axial direction, without unwinding it, while maintaining the coiled form, and progressively heating such extended material.

6. The method consisting in extending a coil of material to be heated in an axial direction, without unwinding it, and heating the extended portion, while moving it into the heating position by a force applied to its unheated portion.

7. The method consisting in extending a coil of material to be heated in an axial direction, without unwinding it, progressively winding it into a heating chamber or furnace and there heating it.

8. The method consisting in extending a coil of material to be heated in an axial direction, without unwinding it, moving successive portions of said material into a heating chamber or furnace by a force applied to the unheated portion of the coil, and heating it in said chamber or furnace.

9. The method consisting in progressively extending a coil of material to be heated in an axial direction, without unwinding it, moving the extended portions progressively into a heating chamber or furnace and progressively heating such portions.

10. The method consisting in progressively extending a coil of material to be

4
heated in an axial direction, without unwinding it, moving the extended portions progressively into a heating chamber or furnace by a force applied to an unheated 5 portion of the coil and progressively heating such portions.

11. The method consisting in extending a coil of material to be heated in an axial direction, without unwinding it, moving the 10 extended portions into a heating chamber or furnace, and there heating said extended portions in coiled form.

12. The method consisting in extending a coil of material to be heated in an axial direction, without unwinding it and heating 15 the extended portion while maintaining its coiled form.

13. The method of progressively heating a continuous length of rod or wire, which 20 method consists in progressively feeding

said rod or wire into the furnace with a predetermined initial curved shape or set corresponding to the curvature of a helical coil of a diameter corresponding to the size of the heating space within the furnace, 25 progressively feeding the successive turns of such coil shaped material so that they hang loosely from a support of relatively small diameter within the furnace, causing said coil to progress along said support axially 30 of the coil and withdrawing the fully heated material from the remote end of the coil.

Signed at North Tonawanda, in the county of Niagara and State of New York, this 24th day of January, A. D. 1916.

WM. B. PEIRCE.
